UNITED STATES PATENT OFFICE.

CARL M. WENDELSTEIN, OF ATTLEBORO, MASSACHUSETTS, ASSIGNOR TO CHARLES D. LYONS, OF ATTLEBORO, MASSACHUSETTS.

DESIGN FOR A BROOCH, BUTTON, OR BUCKLE PLATE OR LIKE ARTICLE OF MANUFACTURE.

SPECIFICATION forming part of Design No. 36,568, dated October 6, 1903.

Application filed September 8, 1903. Serial No. 172,416. Term of patent 3½ years.

To all whom it may concern:

Be it known that I, CARL M. WENDELSTEIN, a citizen of the United States, and a resident of Attleboro, in the county of Bristol and State of Massachusetts, have invented a new, original, and ornamental Design for a Brooch, Button, or Buckle Plate or Like Article of Manufacture, reference being had to the drawing, in which the figure represents a face view of a buckle-plate embodying my new design.

I claim as new and desire to secure by Letters Patent—

The ornamental design for a brooch, button, or buckle plate, or like article of manufacture, herein shown.

In testimony whereof I have signed my name to this specification in the presence of two subscribing witnesses.

CARL M. WENDELSTEIN.
